CLAIM

The ornamental design for a helmet for monitoring brain health as shown and described.

DESCRIPTION

FIG. 1 is a front top perspective view of a helmet for monitoring brain health, showing our new design, shown with the visor portion closed;

FIG. 2 is a top view thereof;

FIG. 3 is a right-side view thereof;

FIG. 4 is a left-side view thereof;

FIG. 5 is a front view thereof;

FIG. 6 is a back view thereof;

FIG. 7 is a bottom view thereof;

FIG. 8 is a front top perspective view of a helmet for monitoring brain health, showing our new design, shown with the visor portion open;

FIG. 9 is a top view thereof;

FIG. 10 is a right-side view thereof;

FIG. 11 is a left side view thereof;

FIG. 12 is a front view thereof;

FIG. 13 is a back view thereof; and,

FIG. 14 is a bottom view thereof.

Portions shown in broken lines are not part of the claimed design.

1 Claim, 14 Drawing Sheets
